V. H. LOFLIN.

SUIT RACK.

APPLICATION FILED JAN. 12, 1917.

1,249,643.

Patented Dec. 11, 1917.

UNITED STATES PATENT OFFICE.

VIRGINIA H. LOFLIN, OF CENTERVILLE, MARYLAND.

SUIT-RACK.

1,249,643.

Specification of Letters Patent. Patented Dec. 11, 1917.

Application filed January 12, 1917. Serial No. 142,064.

To all whom it may concern:

Be it known that I, VIRGINIA H. LOFLIN, a citizen of the United States, residing at Centerville, in the county of Queen Anne's 5 and State of Maryland, have invented certain new and useful Improvements in Suit-Racks, of which the following is a specification.

This invention relates to an improved suit 10 rack and has as its primary object to provide a device of this character more particularly designed for supporting one or more suits of clothes, coats, or other articles of wearing apparel in convenient position.

15 The invention has as a further object to provide a device of this character employing an extensible bracket carrying a number of loops each adapted to receive the usual coat hanger and wherein the said loops will also 20 act to pivotally connect the coacting elements of the bracket.

The invention has as a further object to provide a rack of the above described character wherein the extensible bracket will be 25 held against sagging and will also be supported from the floor by a post so that the said bracket cannot easily become displaced.

Other and incidental objects will appear as the description proceeds and in the drawings wherein I have illustrated the preferred 30 embodiment of the invention and wherein similar reference characters designate corresponding parts throughout the several views:

35 Figure 1 is a perspective view of my improved suit rack showing the bracket thereof extended.

Fig. 2 is a fragmentary side elevation showing the coacting arms provided for 40 holding the bracket against swinging movement and the staple or pin carried by the said arms and arranged to prevent the said bracket from sagging, and

Fig. 3 is a detail sectional view of one of 45 the hanger loops or attaching members carried by the bracket and illustrating the manner in which the said loops are arranged to pivotally connect the lower extremities of the coacting elements of the bracket.

50 In carrying out the invention, my improved suit rack is preferably formed with a supporting post 10 which may be arranged to seat against a wall to be secured thereto by a plurality of lateral lugs 11. At its 55 lower extremity, the post 10 is preferably provided with a foot 12 to rest against the

floor and preferably, the said foot, as well as the lower extremity of the post, is formed to receive screws or other suitable fastening devices so that the lower end of the post 60 may be rigidly held in position.

Extending outwardly from the upper extremity of the post 10 are spaced ears 13 and supported by the said ears, is an extensible bracket 14. This bracket is pref- 65 erably constructed upon the principle of the ordinary lazy tongs, comprising a plurality of crossed bars or slats 15. Pivots connecting the said bars, at their upper extremities, are a plurality of rivets or other 70 suitable fastening devices 16 while similar elements 17 are employed for pivotally connecting the said bars at their points of intersection. The bars 15, at the inner end of the 75 bracket, are received between the ears 13 of the post 10 and are pivotally secured thereto by a bolt or other similar fastening device 18 while a handle or finger receiving loop 19 is pivotally connected to the meeting 80 ends of the terminal bars at the outer extremity of the bracket. For pivotally connecting the meeting ends of the bars 15, at their lower extremities, I provide a plurality 85 of combined pivot and hanger loops 20 of the type particularly shown in Fig. 3 of the drawings. Each of these loops is preferably formed from a length of wire bent adjacent one extremity to provide a lateral lug 21 from which projects a shank 22. This shank 90 is arranged to extend through the meeting ends of a pair of the bars 15 for pivotally connecting the said bars and is then offset as shown at 23. From the offset 23, the length of wire is bent to provide the depending hanger loop when the free extremity of 95 the wire is looped about the shank 22 as shown at 24 to be held in position by the lug 21. The lower terminals of each pair of the bars 15 will thus be held between the loops 24 and the offsets 23 with the shanks 22 of 100 the said hanger loops pivotally connecting the said bars. This provides a very simple and convenient arrangement for connecting the bars 15 at their lower extremities, while at the same time, the hanger loops 20 are 105 also provided for receiving a plurality of suit hangers such as are conventionally illustrated at 25. As will be seen, the bracket 14 is thus disposed to carry a number of the hangers 25 and suits of clothes, coats, or 110 other articles of wearing apparel may be arranged upon the said hangers to be sup-

ported by the bracket. Furthermore, by grasping the handle 19, the bracket may be easily collapsed within a closet, as for instance when a rack is disposed within a closet, or may be extended to project outwardly from the closet wall so that the articles of wearing apparel upon the bracket may be readily removed.

Arranged to project from the upper extremity of the post 10 are spaced lateral arms 26 arranged to extend upon opposite sides of the bracket 14 above the ears 13 to hold the bracket against lateral movement with respect to the said post. These arms 26 will, therefore, materially contribute to the stability of the device and will tend to guide the bracket in its movement when being extended. Formed through the arms 26 to extend longitudinally thereof, are oppositely disposed slots 27 and arranged to roll within the said slots, is a transverse pin 28. The pin 28 is, as particularly shown in Fig. 2, arranged to extend through a slot 29 formed in the uppermost bar 15 of the bracket at its inner extremity. Consequently, when the bracket 14 is extended, the said bar of the bracket will shift the pin 28 to engage within the outer ends of the slots 27 while the pin will move within the slot 29 of the bar 15 to engage within the upper extremity of the said slot with the pin then acting to rigidly support the said bar and limit the bar in its downward pivotal movement. The pin 28 will, therefore, provide a slidable connection between the guide arms 26 and the bracket for holding the said bracket against sagging and will act to communicate any downward stress upon the bracket directly to the post 10 to be supported thereby. A rigid and efficient structure is thus produced and a rack which will be found highly practical and efficient in actual use.

Having thus described my invention, what is claimed as new is:

- 45 1. A device of the character described including a supporting post, an extensible bracket carried thereby, a hanger member carried by said bracket, and guide arms projecting longitudinally from the said post upon opposite sides of the bracket for directing the bracket when being extended and holding the said bracket against swinging movement with respect to the post.
- 50 2. A device of the character described including a supporting post, an extensible bracket carried thereby and formed with a plurality of crossed pivoted elements, spaced arms projecting longitudinally from the post upon opposite sides of the bracket, and
- 55 60 a sliding connection between said arms and

one of said elements at a point intermediate the ends thereof for holding the bracket against sagging.

3. A device of the character described including a supporting post, an extensible bracket carried thereby and formed with a plurality of crossed connecting members, and a combined pivot and hanger element carried by a pair of the said members, the said element being formed from a length of material bent to provide a shank extending through and pivotally connecting the said pair of members with the said shank provided at one extremity with a lug confronting one of the members of said pair and at its opposite extremity with an offset confronting the other member of said pair, the length of material being extended from said offset to provide a loop for receiving a hook and being looped at its free extremity about the said shank to be retained by the said lug with the said pair of members held between the said last mentioned loop and the said offset.

4. A device of the character described including an elongated post formed at its lower extremity with an angularly disposed foot adapted to fit within the angle between a wall and floor for engagement with the floor, an attaching element carried by the upper extremity of the said post for connection to the wall for supporting the said post in upright position, an extensible bracket carried by the post and formed of a plurality of crossed pivotally connecting elements, and a hanger member carried by the said bracket.

5. A device of the character described including a supporting post, an extensible bracket carried thereby, a hanger member carried by said bracket, elongated guide arms projecting laterally from the post at opposite sides of the bracket and formed with oppositely disposed slots, and means slidably fitted within said slots and loosely engaging the bracket for holding the bracket against sagging.

6. A device of the character described including a supporting post, an extensible bracket carried thereby and formed of a plurality of crossed pivotally connecting elements, a hanger member carried by the bracket, elongated guide arms projecting laterally from the post at opposite sides of the said bracket and embracing one of said elements, and a sliding connection between the said element and the said arms for holding the bracket against sagging.

In testimony whereof I affix my signature.

VIRGINIA H. LOFLIN.
